HIGH TRACTION SOLE AND HEEL

Harry A. Husted, St. Clair, Mich.

Application April 28, 1945, Serial No. 590,808

2 Claims. (Cl. 36—59)

1

It is an object of this invention to provide a sole and heel each of which has a tread surface particularly adapting it to use in snow covered hill country.

The above and other objects will be made clear in the following detailed description taken in connection with the annexed drawing, in which:

Figure 1 is a plan view of the improved sole and heel;

Fig. 2 is a section on the line 2—2 of Fig. 1;

Fig. 3 is a section on the line 3—3 of Fig. 1.

There is a sharp distinction in the requirements of a tread for vehicle tires and in the requirements of a tread for a shoe. Generally speaking, a vehicle tire must be designed with a view to meeting a wide variety of conditions and to exerting strong tractive force in a single direction in the plane of the contact of the tire with the ground. A shoe sole representing a relatively small investment may be specialized to meet any particular service. A vehicle tire operates at high rotary speeds and under severe vibration. It is not, therefore, necessary to pay any particular attention to the ability of a vehicle tire to free itself from clogging the tread with snow or mud. In a shoe sole, the element of centrifugal force is entirely lacking and the element of vibration is practically nil. As a result, it is necessary in designing a shoe tread for use in snow or mud to arrange the elements of the tread so as to minimize clogging of the tread by such snow or mud. It is also necessary to take into account the mechanics of human walking. The weight of the body is never equally distributed over the entire area of the sole in contact with the ground, but rather concentration of weight shifts from point to point throughout the sole, depending on the nature of the terrain being covered. In designing a shoe tread, the tread elements must be constructed and distributed to meet these exigencies.

In Fig. 1 there is shown a sole 10 to which is attached a heel 12. Adjacent the toe is a raised area 14, the surface of which is diagonally grooved at 16 to form a plurality of pyramids having rhomboidal bases. The spacing of these pyramids is preferably about $\frac{1}{16}$ inch peak to peak, while the height of the pyramids, base to peak, approximates $\frac{3}{32}$ of an inch. The area 16 terminates inwardly from the toe in a zig-zag line 17.

Spaced from the zig-zag line 17, but following its pattern, is a zig-zag rib 18 followed by similar ribs 18 liberally spaced by substantially the same distance as the first rib 18 is spaced from the line 17. Each of these ribs 18 is surfaced with a plurality of rhomboidal pyramids 20 which are

precisely similar to the pyramids in the area 16, but which are approximately one-half the size of the pyramids in area 16. Each of the ribs 18 is approximately $\frac{1}{16}$ inch wide.

As the sole narrows toward the instep, the overall length of the ribs 18 decreases, and spaced rearwardly from the last of the ribs there is provided a series of transverse ribs 22, 24 and 26, which are semi-cylindrical in cross section, and respectively decrease in diameter toward the instep.

As best seen in Fig. 2, the top side of the sole is recessed to receive a sheet of cork 30. This sheet of cork is provided for the purposes described in detail in co-pending application, Serial No. 590,803, filed of even date herewith.

The heel 12 has at its inner or breast margin a relatively plain space 32 on which may be molded any suitable indicia, such as a trade-mark, the heel size, etc. Adjacent the plain area 32 is a knurled area 34, the surface of which is identical with that of the toe area 14. Adjacent the end of the knurled area 34, and from there to the rear of the heel, there are molded a series of ribs 36 which are semi-cylindrical in cross section, and are separated by grooves 38.

In ordinary walking, the rear end of the heel strikes the ground first, subsequently the entire heel is in contact with the ground before the sole makes contact with the ground. This is particularly true in walking down grade. On a severe up grade, however, the toe touches the ground first, and the heel may not be involved at all. Since normally the heel takes the most severe impact, it is at the heel where ice or snow has the greatest tendency to form a ball and thus to clog the tread. Accordingly, while friction is distinctly desired, it is necessary to minimize the opportunities for anchorage of snow or ice, and thereby to minimize the tendency toward balling. It will be noted that the surface of the heel 12 responds to this principle in that no really deep anchorage is provided. At the extreme toe of the sole, the pressure involved is usually not so great as at the heel, but probably less flexure takes place within the area 14 than at any other part of the sole. Accordingly, there is less tendency for this area to be self clearing, and for this reason an area of minimum anchorage is provided at the toe.

The area occupied by the relatively coarse ribs 18 is the area where maximum flexure occurs, and is also the area which carries most of the tractive effect in walking. Accordingly, the ribs 18 are designed to give a solid bite into snow or mud, and although this design affords excellent an-

chorage which might result in balling, such anchorage is provided in what is substantially a self-clearing area.

The soles and heels are preferably molded of synthetic rubber, since the intrinsic characteristics of such rubber may be accurately controlled. The invention is not, however, limited to any particular formula, nor indeed to synthetic rubber. Various dimensions have been indicated and as a practical matter these are preferred. They are given, however, by way of illustration and not of limitation.

I claim:

1. A sole, a heel attached thereto, said sole and heel being molded of rubber-like material, a tread on said sole and heel, said tread comprising: an area at the toe knurled to provide traction in any direction in the plane of the sole and to provide minimum anchorage normal to said plane; an area at the rear of said heel providing traction in the plane of said heel primarily in the direction of the toe, the remainder of said heel surface substantially duplicating said toe area; and an area

in said sole intermediate said toe area and the shank comprising zig-zag ribs of substantial width and substantially spaced, one from the other, said tread being formed of the material of said sole and heel.

2. A sole, a heel attached thereto, said sole and heel being molded of rubber-like material, a tread on said sole and heel, said tread comprising: an area at the toe knurled to provide traction in any direction in the plane of the sole and to provide minimum anchorage normal to said plane; an area at the rear of said heel providing traction in the plane of said heel primarily in the direction of the toe, the remainder of said heel surface substantially duplicating said toe area; and an area in said sole intermediate said toe area and the shank comprising zig-zag ribs of substantial width and substantially spaced, one from the other, said tread being formed of the material of said sole and heel, the free surface of said zig-zag ribs being knurled to a smaller pattern than said toe area.

HARRY A. HUSTED.
